ATTORNEY

UNITED STATES PATENT OFFICE.

ANDREW KROUSE, OF BRIDGEPORT, CONNECTICUT.

DESIGN FOR A SUPPORT FOR PINCUSHIONS.

SPECIFICATION forming part of Design No. 23,040, dated February 6, 1894.

Application filed December 28, 1893. Serial No. 495,009. Term of patent 3½ years.

To all whom it may concern:

Be it known that I, ANDREW KROUSE, a citizen of the United States, residing at Bridgeport, in the county of Fairfield and State of Connecticut, have invented and produced a new and original Design for Supports for Pin-cushions; and I do hereby declare the following to be a full, clear, and exact description of the invention, such as will enable others skilled in the art to which it appertains to make and use the same.

In the accompanying drawings which illustrate my design Figures 1 and 2 are elevations of opposite sides of a pin cushion support embodying my design.

The leading feature of my design consists in the body of the stand or support shaped like a child's button shoe, with its upper edge scalloped, and with a ribbon represented

around the shoe immediately below such scalloped portion and tied in a bow knot at the side of the shoe.

1 is the body or stand, 2 the scalloped portion at the top thereof, 3 the ribbon represented as extending around the shoe immediately below such scalloped portion, 4 the bow knot into which such ribbon is tied at the side of the shoe, and 5 the cushion.

I claim—

The design for supports for pin cushions substantially as shown in the accompanying drawings.

In testimony whereof I affix my signature in presence of two witnesses.

ANDREW KROUSE.
